UNITED STATES PATENT OFFICE.

JOHN F. FARRINGTON, OF NEW YORK, N. Y., ASSIGNOR TO WESTERN ELECTRIC COMPANY, INCORPORATED, OF NEW YORK, N. Y., A CORPORATION OF NEW YORK.

CIRCUIT FOR AUDIONS.

Application filed October 25, 1920. Serial No. 419,512.

To all whom it may concern:

Be it known that I, JOHN F. FARRINGTON, a citizen of the United States, residing at New York, in the county of the Bronx, 5 State of New York, have invented certain new and useful Improvements in Circuits for Audions, of which the following is a full, clear, concise, and exact description.

The invention relates to circuits for electric space discharge devices and especially to improvements in that part of the circuit shown in White Patent No. 1,195,632, which relates to heating the filamentary cathode of

10 According to the disclosure in that patent, the source of alternating current for heating the filament is connected to the cathodes through a transformer. The grid and anode electrodes are connected to the midpoint of 15 the secondary winding of this transformer in order that there may be introduced into the circuit no fluctuations of a frequency corresponding to an audible frequency such as 60 cycles which is employed for heating 20 the filaments. By this arrangement the average difference of potential at any instant between the three electrodes is independent of the potential applied to the cathode for heating purposes. According to 25 the disclosure in the patent, in case the nature of the circuit is such as to require a plurality of electron discharge devices, a 30 separate transformer winding having a midpoint connection is provided for the cathode of each vacuum tube.

According to the present invention, only a single transformer need be employed in the filament lighting circuit, even though filaments of a plurality of vacuum tubes are 40 required to be heated. This is accomplished by providing a compensating circuit which is common to all of the vacuum tubes. Specifically this arrangement comprises an 45 impedance connected in shunt to the secondary winding of the transformer, the grid and anode electrodes of all the vacuum tubes completing their circuits through the midpoint of this impedance.

A further object of the invention is to 50 employ a plurality of electron discharge devices having different filament resistances in connection with a source of alternating current for heating the filaments and in such a manner that the current flowing to the tube 55 or tubes of low filament resistance may be

reduced without unbalancing the average difference in potential between the cathode and its associated grid and anode. This is accomplished by connecting the filaments in parallel to the terminals of the transformer 60 secondary, which is compensated as above described, and by dividing the resistance which is to reduce the filament current flowing to one or more tubes into two equal parts, each of which is placed in one of the 65 filament leads. The center of this filament then has an average zero potential as in the other cases.

A further object of the invention is to facilitate maintenance of a proper value of 70 voltage between the anode and cathode of an electric space discharge device. This is accomplished by a suitable arrangement of impedances in the circuit of the space current source.

The invention will be described in further detail in connection with the drawings, in which the figure illustrates diagrammatically a radio transmitting circuit embodying the invention.

Referring in detail to the drawings, the circuit chosen to illustrate the invention is a radio transmitting circuit, although the scheme of lighting the filaments may be applied to any type of circuit.

In the figure the vacuum tube 1 is a speech current amplifier for modulating by means of the tube 2 the high frequency currents which are generated by the tube 3 and amplified by the tube 4. The modulated current is supplied to the radiating system 5. The modulating tone may be derived from the transmitter 6 in circuit with the battery 7 and the primary winding of transformer 8. The secondary winding of this transformer is shunted by a high resistance 9 of the order of 100,000 ohms. One end of resistance 9 is connected to the grid of vacuum tube 1, the other end being connected through the battery 10 to ground. The battery 10 serves to make the grid normally either negative or positive a desired amount with respect to the cathode. The grid circuit is completed from ground through the midpoint 11 of resistance 12 connected in shunt to the transformer 13 in circuit with the A. C. generator 14, which supplies heating current for the filaments. The resistance 12 should be of a value comparable with the filament resistance of one of the 110

tubes in order to not waste the anode circuit energy. The current flowing to the filaments may be regulated by the resistance 15. By grounding the cathode, the capacity 5 to ground of the connecting wires is reduced thereby preventing singing of the repeater. Furthermore, since the path to ground is symmetrical, no unbalance can occur due to the use of alternating current for heating 10 the filaments.

Connected to the secondary of the transformer 13 are the leads or bus bars 16 and 17, across which are connected the filaments of the various tubes. In case the filament 15 of the low power tube 1 has a lower resistance than the filaments of the other circuits, the current to this filament may be reduced without introducing any unbalance by employing equal resistances 18 and 19 in the 20 leads of this filament. If the filaments of the tubes 2, 3 and 4 all have the same resistance, they may be connected directly across the leads 16 and 17 without the use of the resistances such as 18 and 19.

25 The anode circuits of the tubes may be supplied with direct current from the generator 20 having the filter 21 in circuit therewith to reduce the effect of commutator ripples. One lead from generator 20 is 30 taken to the midpoint 11, the other lead is taken (a) through high resistance 22 to the anode of vacuum tube 1, (b) through choke coil 23 to inductance 24 and the anode of vacuum tube 2 on one hand and through inductance 25 to the anode of vacuum tube 4 on the other hand, and (c) through resistance 26 and inductance 27 to the anode of vacuum tube 3. Inductance 24 is a high frequency choke coil to prevent undesired 40 oscillation of the circuit.

The high resistance path 28 to ground may be employed to prevent the full potential of generator 20 from being applied between the cathode and anode of tube 1 in 45 the event that (1) the impedance of tube 1 is accidentally made infinite due to not closing the filament circuit before closing the anode circuit, or (2) the impedance becomes too high (with reference to resistance 22) 50 due to too high a negative potential on the grid from battery 10. If generator 20 supplies 1500 volts, and if tube 1 is built to stand only 500 volts, then resistance 28 should be one-half the value of 22 and both 55 of them large as compared to the normal operating impedance of the tube. In one case a tube has been employed corresponding to tube 1 and having a cathode-anode impedance of about 5000 ohms, resistance 22 being 30,000 ohms, and resistance 28, 15,000 ohms. Tubes 1 and 2 are separated for direct current by the blocking condenser 29. The grid circuit for tube 2 may include a choke coil 30 connected through battery 60 31 to ground. Between the grid and anode

of oscillator 3 may be connected condensers 32 to 29 inc., and the midpoint of condensers 33 and 34 is connected to the cathode of tube 3. The condensers 37, 38 and 39 may be put in or out of circuit by the switch 40. The 70 grid-anode circuit of oscillator 3 also includes an inductance 41, which may be put in or out of circuit by a switch 42, resistance 43 and inductance 44. The grid circuit of tube 3 may be completed through inductance 45 and high resistance 46 to ground. The path to ground including condenser 50 has been found to prevent objectionable singing of the circuits. 75

The amplified modulated high frequency 80 current appearing in the output circuit of tube 4 is supplied through the condensers 47 and 48 to the coil 49, which may be variably connected in the antenna circuit. Condensers 47 and 48 by-pass high frequency 85 and offer high impedance for audio frequency current.

It will be apparent that the application 90 of the features of the invention is not limited to the arrangement of discharge devices specifically shown in the drawing, and that the vacuum tubes may be connected in tandem or in multiple, and these tubes may be employed in any well-known manner as detectors, power limiters or the like without 95 being restricted to the particular use herein described.

What is claimed is:

1. The combination of a circuit comprising 100 a plurality of electron discharge devices each having a cathode and an anode, a source of alternating current for heating said cathodes, a transformer having a primary winding and a secondary winding for connecting said source to said cathodes, and a compensating circuit common to said cathodes for suppressing the difference in potential between the cathodes and anodes due to the use of alternating current for lighting said 105 cathodes.

2. A circuit comprising a plurality of 110 electron discharge devices delivering electromotive force, each device having a cathode adapted to be connected to a source of alternating current, and a compensating circuit common to said cathodes, for preventing the alternations of said current in said cathodes from causing variations in the electromotive force output of said devices.

3. The combination of a plurality of 115 electron discharge devices connected in tandem each having a cathode, an anode and a control electrode, a source of alternating current for heating said cathodes, a transformer for connecting said source to said cathodes, an impedance in shunt to the secondary winding of said transformer, and connections from an intermediate point of said impedance to the control electrodes and anodes 120 of said tubes.

4. A circuit comprising a plurality of electron discharge devices each having a cathode and an anode, the cathode for one of said tubes having a resistance lower than the cathode resistance of another of said tubes, equal impedances in each of the leads of the cathode of lower resistance, and means for heating said cathodes with alternating current. 5. A circuit comprising a plurality of electron discharge devices each having a cathode and an anode, the cathode of one of said tubes having a resistance lower than the cathode resistance of another of said tubes, and means for heating said cathodes with alternating current while maintaining substantially a zero average difference of potential between the cathodes and their respective anodes. 10. 6. The combination of a circuit comprising a plurality of electron discharge devices each having a cathode and an anode, a source of alternating current for heating said cathodes, a compensating circuit common to said cathodes for suppressing the difference in potential between the cathodes and anodes due to the use of said alternating current for heating said cathodes while permitting said alternating heating current to heat said cathodes, and means associated with one of said cathodes for reducing the current flow thereto while maintaining substantially a zero average difference of potential between said last-mentioned cathode and its associated anode. 15. 7. A circuit comprising an electron discharge device having a cathode and an anode, a source of current for heating said cathode, and equal impedances to said current, connecting the terminals of said source to the terminals of said cathode, respectively. 20. 8. A circuit comprising an electron discharge device having a filamentary electrode and an anode, means for heating said filamentary electrode with alternating current, and equal impedances to said current in each of the leads of the filamentary electrode. 25. 9. The combination of a plurality of electron discharge devices connected in tandem each having a cathode, an anode and a control electrode, a source of alternating current for heating said cathodes, a transformer for connecting said source to said cathodes, an impedance in shunt to the secondary winding of said transformer, connections from an intermediate point of said impedance to said control electrode and anode, and equal impedances in the leads of one of said cathodes. 30. 10. An electron discharge device having an electrode, means including a source of alternating current and a transformer connecting said source and said electrode for heating said electrode by alternating current, and a path to ground for said electrode, said path comprising a resistance in shunt to said electrode, and a connection from the electrical midpoint of said resistance to ground. 35. 11. A vacuum tube circuit comprising an electron discharge device having a cathode, anode and grid electrodes, and means for heating said cathode, said means including a source of alternating current and a transformer connecting said source and said cathode, and said circuit comprising also an impedance in shunt to said cathode, a connection from an intermediate point of said impedance to one of said electrodes, and a connection from an intermediate point of said impedance to ground. 40. 12. A system comprising an electric discharge device having an anode and a cathode, a resistance, a source of electromotive force for supplying voltage across said anode and cathode through said resistance, a load circuit for said device, said load circuit being connected across said resistance, and means for protecting said device against excessive voltage from said source, said means comprising a resistance shunted across said anode and cathode. 45. 13. A relay system comprising an electron tube having an anode and a cathode, and means for controlling current flow between said anode and cathode, a resistance having a value high relative to the anode-cathode resistance of said tube, a source of electromotive force for supplying voltage across said anode and cathode through said resistance, a load circuit for said tube, said load circuit being connected across said resistance, and means for protecting said tube against excessive voltage from said source, said means comprising a resistance shunted across said anode and cathode. 50. 14. In witness whereof, I hereunto subscribe my name this 23rd day of October, A. D., 1920. JOHN F. FARRINGTON.
